US00D893922S

(12) **United States Design Patent** (10) **Patent No.:** **US D893,922 S**
DeJesus et al. (45) **Date of Patent:** **** Aug. 25, 2020**

(54) **RETAIL FIXTURE**

- (71) Applicant: **Apple Inc.**, Cupertino, CA (US)
- (72) Inventors: **Manuel DeJesus**, San Francisco, CA (US); **Joshua Robert Edwards**, Santa Cruz, CA (US); **Jean-Marc Gady**, Los Altos, CA (US); **Wesley Bryan Hamm**, San Francisco, CA (US); **Russell John Kaaihue Heirakuji**, Cupertino, CA (US); **Allison Inouye**, San Francisco, CA (US); **Moritz Wilsberg**, Rheinbreitbach (DE)
- (73) Assignee: **Apple Inc.**, Cupertino, CA (US)

(**) Term: **15 Years**

(21) Appl. No.: **29/727,168**

(22) Filed: **Mar. 9, 2020**

Related U.S. Application Data

- (63) Continuation of application No. 29/655,963, filed on Jul. 9, 2018, now Pat. No. Des. 877,547.

(57) **CLAIM**

The ornamental design for a retail fixture, as shown and described.

DESCRIPTION

FIG. 1 is a top front perspective view of a retail fixture showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top front perspective view of another retail fixture showing the claimed design;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.

The broken lines in the figures show portions of the retail fixture that form no part of the claimed design.
